Albert P. Ball, Detroit, Mich., assignor to Briggs Manufacturing Company, Detroit, Mich., a corporation of Michigan

Application February 10, 1934, Serial No. 710,635

8 Claims. (Cl. 155—50)

This invention relates to chairs and articles of furniture which may be used as such or which may be utilized in vehicle body constructions to provide the seats therein.

5 One of the objects of this invention is to provide a construction for a chair or other article of furniture in which a frame is formed of tubular metal stock bent to form a floor engaging portion, a vertically spaced seat supporting portion, a back portion, and arm rests, the floor engaging portion and the seat or arm rest portion being connected together by means of coil spring members permitting vertical angular movement of the seat supporting portion 10 relative to the floor engaging portion.

Other objects of this invention will appear in the following description and appended claims, reference being had to the accompanying drawing, forming a part of this specification wherein like reference characters designate corresponding parts in the several views.

20 Fig. 1 is a perspective view of a chair constructed in accordance with my invention showing a fragmentary view of a covering applied to the chair frame.

25 Fig. 2 is an enlarged fragmentary view partially in section showing the method of connecting the floor engaging portion and the seat portion of the chair by means of the coil spring members.

30 Fig. 3 is a fragmentary elevation partially in section taken on the line 3—3 of Fig. 2 in the direction of the arrows.

Fig. 4 is a sectional view taken substantially on the line 4—4 of Fig. 2 in the direction of the arrows.

35 Fig. 5 is a sectional view taken substantially on the line 5—5 of Fig. 2 in the direction of the arrows.

40 Before explaining in detail the present invention it is to be understood that the invention is not limited in its application to the details of construction and arrangement of parts illustrated in the accompanying drawing, since

45 the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

50 A chair or like article of furniture embodying the invention herein may be constructed of a plurality of separate pieces of tubular metal

stock. As shown in Fig. 1 such a construction may comprise a floor engaging member A, a seat support and back member B, and a back brace and arm member C.

The floor engaging portion A is preferably, 5 although not necessarily, substantially U-shaped in plan view and comprises a rear portion 10 and spaced parallel side portions 11 extending forwardly therefrom, the side portions 11 being

bent upwardly at their ends to form the upwardly extending leg portions 12. A brace 13 is secured adjacent the ends of the upwardly extending leg members 12 and holds the forward portion of the floor engaging member A in a predetermined position while at the same time 15 lending strength thereto. The seat support and back member B may also be formed of a single piece of tubular metal stock, the back portion being substantially U-shaped in elevation and comprising a top rail portion 14 and parallel spaced

10 side portions 15 having seat supporting portions 16 extending substantially at right angles 20 forwardly therefrom. The back brace and arm member C may likewise be formed of a single piece of tubular metal stock formed substan-

25 tially U-shaped in plan view to provide a back brace 17 having spaced apart parallel sides 18 extending forwardly therefrom and furnishing the arms of the chair, the ends of the members 18 being bent substantially at right angles 30 and extending downwardly therefrom to provide portions 19 to which the seat supporting members 16 are joined as by welding. The sides 35

15 of the seat support and back member B are secured to the member C by pins 20 or the like. The arm portions 18 may be provided with arm 40

rest pads 21 formed of wood or any other suitable material, these pads being provided with relatively wide crowned upper surfaces upon 45

which the arms of the occupant of the chair may rest comfortably. The underside of each of the arm rest portions is formed with rabbed portions 22 to receive the top of the tubular stock forming the arms 18, the pads 21 being secured to the arms 18 by any suitable

means as, for example, clamps, staples or the like which are not here shown.

The seat support and back member B joined as above described to the arm and back brace member C acts as a unit and is secured to the floor engaging member A through coil units 30

formed of spring material such as spring steel rod stock or the like. As shown in detail in Fig. 2, each of the coil units 30 comprises nested

30 spring coils 31 and 32. One end of each of 45

50 the coil units 30 is secured to the underside of the seat support and back member B and the other end of each of the coil units 30 is secured to the underside of the floor engaging member A. The coil units 30 are secured to the underside of the floor engaging member A by any suitable means as, for example, clamps, staples or the like which are not here shown.

the coils 31 and 32 is placed in an adapter 33, and these adapters are telescoped into the open ends of the members 19. The other or lower end of each of the coils 31 and 32 is secured 5 to an adapter 34, and these adapters are telescoped into the open ends of the legs 12. A resilient buffer 35 formed of rubber or other suitable material has an opening through which one end of each of the springs 31 and 32 extends 10 into the adapter 34. Since the base portions 35c of the rubber pieces are interposed between the abutting ends of the members 19 and 12, it will be seen that they are maintained in position against displacement by the ends of the 15 springs 31 and 32 passing therethrough. Each member 35, as shown in Fig. 4, is substantially U-shaped in plan view and has an upstanding lip 35a formed integrally with the base portion 35b. It will be apparent that the members 35 20 act as resilient buffers between the opposed terminal meeting ends of the members 19 and 12. Moreover, the upwardly extending and outwardly curved resilient lip 35a provides a jacket or cap at all times embracing the lower end 25 of the member 19. This curved or convex shaped lip is so formed with the proper radius of curvature as to provide a sufficient space or recess within which the terminal end of member 19 is free to move outwardly when the seat is 30 oscillated, as shown in dotted lines in Fig. 2. The upper portion of the lip 35a will yield sufficiently to accommodate this movement while at all times confining the terminal end of member 19 and thus maintaining a closed joint between the ends of members 19 and 12 regardless of the relative movement thereof.

The back of each of the members 19 is cut away a suitable distance along the lower end thereof as at 40 (Figs. 3 and 4) in such a manner that the lower ends of the members 19 are substantially U-shaped in cross section and are open at the rear to receive and house a portion of the coils 30. This construction permits the tubular members 12 and 19 to be connected together in vertical alinement and in substantially abutting relation by the spring coils and provides sufficient clearance so that the tilting movement of the unitary frames B and C of the chair relative to the floor engaging frame A 50 is permitted without binding or interference.

The seat proper may be formed of any desired type of upholstery as, for example, a fabric 45 which may be secured to each of the members 16. The back also may be upholstered in any 55 desired manner as, for example, by means of the fabric 46 which may be secured to the members 15. The particular type of upholstery forms no part of the present invention and is therefore not described in greater detail, it being understood that instead of the fabric portions 45 and 46 any part or all of the framing may be enclosed, if desired, with any suitable type of upholstery material.

The coils 30 are sufficiently resilient to permit 65 vertical angular movement of the members B and C as a unit and to restore the parts to the original relative positions. The portions B and C preferably form substantially a rigid unit adapted to rock downwardly relative to the substantially rigid floor engaging member A when 70 in the position shown in Fig. 1. Thus the members B and C as a unit oscillate or swing about a point which is determined by the location of the connecting coils 30.

The tubular metal stock from which the mem-

bers A, B and C may be formed in a preferred construction may be seamless steel tubing or the like. The frame members may be formed of other suitable material and may each be formed of a single piece or of separate pieces of stock 5 as may be preferred. In any case, the movement of the seat portion relative to the floor engaging portion is permitted by the coils 30 and it will be seen that the improved construction is such that the coils 30 may be readily 10 removed for replacement purposes.

I claim:

1. A frame for a chair or like article of furniture including a substantially U-shaped floor engaging member formed of tubular stock having 15 the ends thereof extending vertically to form upright leg portions, a horizontal seat-forming member terminating in a back portion extending substantially vertically thereof, arm members secured to said seat-forming member and terminating in substantially vertical end portions, the end portions of said upright leg portions and said arm members being substantially alined, and means connecting the respective alined portions comprising a plurality of resilient coils each having 20 ends projecting outwardly in opposite alined directions therefrom, one of the ends of a coil being extended into the end of an arm member and the other end of said coil being extended into the end of the alined leg portion, thereby 25 to yieldably connect said arm member and seat-forming member as a unit with said floor engaging member.

2. A frame for a chair or like article of furniture comprising a plurality of pieces of tubular 30 metal stock bent to provide a floor engaging unit including a substantially U-shaped portion adapted to rest upon the floor, said portion having its free ends turned upwardly to provide upright hollow legs, a horizontal seat, a back 40 and arm rests secured together as a unit, said arm rests having their free ends providing depending tubular extensions substantially alined with and in juxtaposition to said upright legs, and a plurality of spring coils each having oppositely extending free end portions telescoped with the juxtaposed ends of said depending tubular extensions and said upright hollow legs and permitting oscillation of the seat, back and arm rest portions as a unit relative to said floor engaging unit about an axis lying within said 45 spring coils.

3. A frame for a chair or like article of furniture, comprising a length of tubular stock bent to provide a rigid one piece seat and back frame, 55 a second length of tubular stock bent to provide a rigid one piece frame forming a back brace and arm members having depending ends and secured to said seat and back frame, a third length of tubular stock bent to provide a rigid 60 one piece floor engaging frame having front upright legs, a pair of spring coils having certain ends thereof detachably telescoped into said legs and having other of the ends thereof telescoped into the depending ends of the arm members thereby to provide a single axis for relative oscillatory movement of said first-named frames and said floor engaging frame.

4. A chair or the like comprising a frame 70 formed of metal stock shaped to provide a floor engaging portion having upright tubular leg portions, a horizontal seat portion, a back portion and arm rest portions, said seat and arm rest portions being joined as a unit and having de-

5 pending tubular extensions substantially abutting the ends of said leg portions, and spring coils disposed below said seat portion and having certain of the ends thereof inserted in the ends of said tubular extensions and having other ends thereof inserted in the ends of said upright tubular leg portions.

5. A chair or the like comprising tubular metal stock fashioned to provide a floor engaging portion having upright leg portions, a horizontal seat portion, a back portion and arm rest portions, said seat and arm rest portions being joined as a unit and having depending extensions alined with said leg portions, spring coils 10 disposed below said seat portion and having certain of the ends thereof inserted in the ends of said extensions and having other ends thereof inserted in the ends of said upright leg portions, and a yieldable cap closing the joint between 15 20 said extensions and leg portions.

6. A chair comprising a unitary seat and back frame formed of tubular stock, a unitary floor engaging frame also formed of tubular stock, said frames having front vertically alined leg 25 25 members terminating substantially in abutting relation, spring coils telescoping with and joining said leg members together, and yieldable

means closing the joint between said abutting members.

7. A chair comprising a unitary seat and back frame, a unitary floor engaging frame, said frames being formed from tubular stock and having front vertically alined leg members terminating substantially in abutting relation, and spring coils having oppositely extending end portions telescoping with and joining said leg members together, said coils having portions of the 10 convolutions thereof disposed within the area of certain of the leg members.

8. An article of furniture comprising a floor engaging tubular metal frame having rigid front upright leg portions and a seat, a back and arm 15 rest frame formed from tubular stock and having depending front extensions provided with cut-away portions, and resilient coils partially nested in the cut-away portions and having oppositely projecting ends, certain of said ends 20 being secured in the upper ends of said leg portions, other of said ends being secured in the lower ends of said extensions, said coils being transversely alined and providing the sole means 25 for permitting relative oscillatory movement of said frames.
